UNITED STATES PATENT OFFICE.

MAX PETER SEGEBARTH, OF BAD REICHENHALL, GERMANY.

THERAPEUTIC APPARATUS.

1,071,591.

Specification of Letters Patent. Patented Aug. 26, 1913.

Application filed December 21, 1912. Serial No. 737,941.

To all whom it may concern:

Be it known that I, MAX PETER SEGE-
BARTH, a subject of the German Emperor,
residing at Bad Reichenhall, Germany, have
5 invented certain new and useful Improve-
ments in Therapeutic Apparatus, of which
the following is a specification.

My invention relates generally to thera-
peutic apparatus and has more particular
10 reference to apparatus of this type wherein
patients are treated in an air chamber or
compartment, the air in such chamber being
either compressed or rarefied as the nature
15 of the treatment to be given the patient may
require.

The primary object of the invention is to
provide means whereby any openings to
such chamber, such as windows and doors,
will automatically respond to the changes
20 in pressure within the chamber, and will
at all times tend to keep said chamber closed
air tight.

In carrying the invention into practice, I
provide doors, and windows in some cases,
25 which press inwardly when the air within
the chamber is rarefied, and press outwardly
when the air within the chamber is placed
under compression.

The invention may be constructed in sev-
30 eral forms, as for example by providing
double doors and windows, one sash of
which may be opened outwardly and the
other opened inwardly; or I may provide
35 single doors and windows movable between
oppositely disposed abutments or insulating
strips; or I may provide revoluble doors
and windows movable between adjustable
stops or abutments.

The form of invention employing double
40 doors and windows has been illustratively
exemplified in the accompanying drawing,
in which—

Figure 1 is a schematic plan view of an
installation embodying my invention; and
45 Fig. 2 is a vertical section of the air chamber
or compartment.

Referring to the drawing by reference
characters, the numeral 10 designates, gen-
erally, a plant by means of which the air in
50 the chamber or compartment may be com-
pressed or rarefied. Pipes 11 lead from the
plant 10 to the chamber *r*. One of the walls
of the chamber *r* is provided with a suitable
55 opening 12 which provides for ingress to
and egress from the chamber *r*. On opposite
sides of the wall containing the opening 12

are provided brackets 13 and 14 having the
doors *n* and *o*, respectively, pivoted thereto
at the points 15. The door *o* is arranged to
open inwardly in relation to the chamber *r*, 60
while the door *n* is arranged to open out-
wardly in relation to the chamber. When
the air within the chamber *r* is under com-
pression the door *o* will be tightly forced
against the bracket 13 which is preferably 65
made of a substantially air tight material.
When the air within the chamber is rare-
fied, thus producing a partial vacuum within
the chamber, the doors *n* and *o* will be sub-
jected to a suction action, the door *o* being 70
opened while the door *n* is firmly drawn
against the bracket 14 and thus tightly held
in position.

The brackets 13 and 14 are preferably an-
gular and the free edges of the doors *n* and
75 *o* are preferably notched as indicated by
the numeral 16 so that when the doors are
subjected to either pressure or to suction
the notched parts 16 will take over the angu-
lar portions of the brackets and thus fit 80
snugly in position. As above indicated win-
dows may also be provided, the construction
thereof resembling generally that of the
doors *n* and *o*.

In the drawing I have shown windows *p* 85
and *q* which are pivoted to opposite sides of
brackets 17 and 18, respectively, by means of
the pivot pins 19. The brackets 17 and 18
are angular, like the brackets 13 and 14, and
the free edge of each window is notched or 90
undercut as at 20 so that when the windows
engage the angular portions of the bracket a
snug fit will result. When the pressure
within the chamber *r* is greater than atmos-
pheric pressure the windows *q* will be forced 95
outwardly and firmly pressed against the
bracket 18. When the air within the cham-
ber *r* is rarefied suction will tend to open
the window *q* and draw the window *p*
100 tightly against the bracket 17.

By the foregoing arrangement I provide
a structure wherein any openings in the
wall thereof may be automatically closed
air tight by the character of the pressure
prevailing within the chamber. 105

While in the present specification, I have
referred specifically to doors and windows,
it will be obvious that the invention is ap-
plicable in any connection where an opening
in a chamber of the kind referred to is to be 110
closed by any closure which has movement
relative to such opening. I desire it to be

understood, therefore, that I do not confine my invention to the details of structure hereinbefore described, and that such details have been given merely to facilitate a full understanding of the invention.

I claim:

1. Therapeutic apparatus embodying therein a chamber provided with an opening leading to the interior of said chamber, 10 movably mounted means whereby said opening may be closed, and means for moving said movably mounted means, said second named means including mechanism for producing compression or rarefaction of the 15 air within said chamber.
2. Therapeutic apparatus embodying therein a chamber having an opening in its wall, a door pivotally mounted on the outside of one of the walls and adjacent the 20 opening therein, a second door pivotally mounted on the inside of the opposite wall and adjacent said opening, and means for varying the pressure within the chamber to selectively operate either of said doors to 25 close said opening air tight.
3. Therapeutic apparatus embodying therein a chamber having an opening in one of its walls, a pair of doors pivotally

mounted adjacent said openings and adapted to open inwardly and outwardly respectively in relation to said chamber, and means for either compressing or rarefying the air within said chamber to operate either of said doors automatically to close the same air tight.

4. Therapeutic apparatus embodying therein an air chamber having an opening in one of its walls, angular brackets secured opposite to each other to the walls forming said opening, a door pivotally carried by each bracket said doors being mounted on opposite faces of said brackets respectively, notches formed at the free edges of said doors and adapted to snugly fit over the angular portions of said brackets, and means for producing variations of pressure within said chamber whereby said doors are automatically actuated to close said chamber air tight.

In testimony whereof I have affixed my 50 signature in presence of two witnesses.

MAX PETER SEGEBARTH.
